UNITED STATES PATENT OFFICE.

JAMES S. WESTHAFER, OF BRAMAN, OKLAHOMA.

DIRIGIBLE-LAMP MECHANISM.

1,257,430.

Specification of Letters Patent. Patented Feb. 26, 1918.

Application filed November 2, 1916. Serial No. 129,136.

To all whom it may concern:

Be it known that I, JAMES S. WESTHAFER, a citizen of the United States, residing at Braman, in the county of Kay, State of Oklahoma, have invented a new and useful 5 Dirigible-Lamp Mechanism; and I do hereby declare the following to be a full, clear, and exact description of the invention, such as will enable others skilled in 10 the art to which it appertains to make and use the same.

This invention relates to an improved 15 dirigible lamp mechanism for automobiles, and an object of this invention is to provide means whereby the lamps, when the front wheels are moved toward the right or 20 the left, will correspondingly move, that is, when such movement of the lamps is desired by the operator.

25 A further object of the invention is to provide means for so operating the lamps that the rays from the lamps may extend straight ahead, while the wheels turn toward the right or the left, or may be 30 thrown correspondingly with or just the opposite to the direction of the wheels.

Further, the invention aims to provide 35 means whereby the lamps may be oscillated vertically to throw the rays from the lamps upon the ground, close to the front of the machine, or farther from the machine, without operating the lamps laterally, or at the same time the lamps are moved pivotally toward the right or the left.

35 In practical fields, the details of construction may necessitate alterations falling within the scope of what is claimed.

The invention comprises further features and combination of parts, as hereinafter 40 set forth, shown in the drawings and claimed.

In the drawings:—

Figure 1 is a view in side elevation and partly in section of the hood portion of an 45 automobile, showing the improved lamp mechanism as applied.

Fig. 2 is an enlarged detail perspective view of the lamp mechanism removed.

Fig. 3 is a detail view in elevation and 50 partly in section, more clearly showing the means whereby the lamps may be oscillated vertically.

Fig. 4 is a detail view of the ball or universal joint between the parts of the means 55 used for moving the lamps pivotally in a vertical direction.

Fig. 5 is a plan view of the lever arm and segment rack mechanisms for moving the lamps laterally or vertically, illustrating said mechanism as applied to the steering column.

Fig. 6 is a sectional view on line 6—6 of Fig. 5.

Referring more especially to the drawings, 1 and 2 designate arms, which, as 65 shown, may be secured by bolts or other suitable means 3, to any part of the hood 4, that is, to any part that is convenient. These arms have laterally extending portions 5, which terminate in bearing brackets 6, in the arms or ears 7 of which the vertical rods or supports 8 are mounted, in order to rock horizontally. The upper ends of the rods or supports 8 have forks 9, in which the rods or supports 10 are pivoted, 75 as shown at 11. The usual lamps 12 are carried by the rods 10 at their forward ends, while the rear ends of the rods 10 are provided with universal or ball joint connections 13 to the links 14. The lower 80 ends of the links 14 are connected to the connecting rods 15, by means of the universal or ball joints 16. The lower portions of the rods 8 terminate in rearwardly extending arms 17, the extremities of which 85 are connected by the bar 18, rising upwardly from which substantially centrally is a pin 19. A bracket 20 and a pin 21, are each carried by the under part of the hood 4. The lower end of the bracket 20 90 is provided with forks 22, between which on a pin 23 an angular lever 24 is pivoted. This lever 24 has long and short arms 25 and 26. The long arm 25 is slotted, to receive and permit movement of the connecting rod 15. This elongated slot 27 extends 95 forwardly and rearwardly, and upon examining the drawings it will be seen that when the angular lever 24 is moved pivotally, the lamps will oscillate vertically, so as to throw 100 the rays from the lamps down directly in front of the automobile or at a greater distance therefrom. Mounted pivotally upon the pin 21 is an angular lever 28 having long and short arms 29 and 30, there being 105 an elongated slot 31 in the long arm for the reception of the vertically extending pin 19 of the bar 18. By virtue of oscillating lever 28 horizontally in one direction or the other, the long arm 29 will move toward 110 the right or the left, which, through the medium of the bar 18, will transmit move-

ment to the vertical rods 7, to cause the lamps 12 to move toward the right or the left. The vertical rods 8 are prevented from axial movement vertically by the collars 32, one above and one below the upper ear or lug of each of the brackets 6. Collars 33 and 34 are secured by screws 35 upon the steering column 36. The collar 33 is provided with diametrically oppositely disposed segment racks 37 and 38, and mounted in bearings 39 and 40 of both collars are rods 41 and 42. Secured upon the rods 41 and 42, by means of suitable pins are collars 43, upon opposite sides of the bearings 40, to prevent axial movement of said rods 41 and 42. The lower ends of the rods 41 and 42 are provided with arms 45 and 46 to which the links 44 are connected. These links respectively are connected to the arms 26 and 30 of the levers 25 and 28. The upper ends of the rods 41 and 42 have secured thereto levers 47 and 48, which are provided with downwardly extending arms 49, in pockets 50 of which, as shown in Fig. 6, spring pressed dogs 51 are mounted, to ride over the teeth 52 of the segment racks 37 and 38. It is to be noted that by moving the lever 47, thus rocking the rod 41, the respective spring pressed dogs 51 of the arm of the lever 47 forcing over the teeth of its respective rack, the link 44 which is connected to the arm 30 of the lever 28, will move forwardly or backwardly, thereby rocking the lever 28, which will in turn oscillate the lamps horizontally. By moving the lever 48, and rocking the rod 42, the angular lever 24 will oscillate vertically, which, in turn, will move or oscillate the rods 10 vertically through the medium of the links 14 and the connecting rod 15, thereby oscillating the lamps vertically. It is to be noted that the above movements of the lamps can be accomplished simultaneously or separately.

46 The invention having been set forth, what is claimed as new and useful, is:—

1. In combination, a pair of arms to be carried by the hood of an automobile and having brackets at their outer lateral ends,

vertical rods mounted in bearings of said brackets to rock, and provided with rearwardly extending arms at their lower ends, rods pivoted in the upper ends of said vertical rod to oscillate vertically and provided with lamps at their forward ends, links connected by universal joints to the second rods, a connecting rod connected to the lower ends of said links by universal joints, a connecting bar connected to the rearwardly extending arms of the vertical rods, and means having loose connections with said connecting rod and designed to be oscillated vertically to move the lamps vertically, and means to be oscillated and connected to said connecting bar loosely, whereby the vertical rods may be oscillated horizontally, to correspondingly move the lamps.

2. In combination, a pair of arms adapted for connection to the hood of an automobile and having vertical brackets at their lateral ends, vertical rods mounted in bearings of said brackets to rock horizontally and having means to prevent axial movement of said rods, said vertical rods having rearwardly extending arms at their lower ends, a bar connecting said arms, whereby said vertical rods may rock in unison and correspondingly, rods pivoted to the upper ends of said vertical rods and having lamps on their forward ends and adapted to oscillate vertically, vertical links having universal connections with the rear end of the second rods, a bar having its opposite ends provided with universal connections to the lower ends of said links, and means carried on the steering column adjacent the steering wheel of the automobile and having connections with said connecting bars respectively whereby said lamps may be moved horizontally and vertically.

In testimony whereof I have signed my name to this specification in the presence of two subscribing witnesses.

JAMES S. WESTHAFER.
